UNITED STATES PATENT OFFICE.

WILLIAM M. LARSEN, OF DECORAH, IOWA.

DESIGN FOR A MEMBER FOR MATCH-LIGHTERS.

SPECIFICATION forming part of Design No. 30,591, dated April 18, 1899.

Application filed January 26, 1899. Serial No. 703,388. Term of patent 7 years.

To all whom it may concern:

Be it known that I, WILLIAM M. LARSEN, of Decorah, in the county of Winneshiek and State of Iowa, have invented and produced a new and original Design for a Member for Match-Lighters, of which the following is a full, clear, and exact specification.

Reference is to be had to the accompanying drawing, forming part of this specification, in which the figure is a perspective view of a member of a match-lighter showing my design.

The design consists of the member B of a match-lighter, having at one end the roughened surface B' in the shape of transverse ridges, said surface terminating a distance

from lugs D, the said lugs being located approximately midway of the length of the member B and appearing integral therewith, the member having its other end terminating in a flange E, having its extremity beveled.

The leading feature of my design consists of the member B, having a roughened surface B', the lugs D, and the flange E, having its extremity beveled.

I claim—

The design for a member of a match-lighter, herein shown and described.

WILLIAM M. LARSEN.
